United States Patent Office

Des. 231,076
Patented Apr. 2, 1974

231,076

SAW HANDLE

Arne Carlsson, Edsbyn, Sweden, assignor to Edsbyns
Industri Aktiebolag, Edsbyn, Sweden

Filed Dec. 22, 1971, Ser. No. 211,163

Term of patent 14 years

Int. Cl. D8—99

U.S. Cl. D8—97

FIG. 1

FIG. 2

FIG. 3

FIG. 1 is a perspective view of a saw handle;
FIG. 2 is a side view of the saw handle showing the
opposite side from that illustrated in FIG. 1, and
FIG. 3 is an end view of the saw handle taken from
the left of FIG. 2.

The broken line disclosure of a saw blade is for illustrative purposes only.

I claim:

The ornamental design for a saw handle, as shown and described.
